UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

SCOOP WASHING-CYLINDER.

1,097,510.

Specification of Letters Patent.

Patented May 19, 1914.

Application filed September 12, 1910. Serial No. 581,528.

To all whom it may concern:

Be it known that I, WILLIAM BARTHOLOMEW, a citizen of the United States, residing at Chicago, county of Cook, State of Illinois, have invented certain new and useful Improvements in Scoop Washing-Cylinders, of which the following is a specification, reference being had therein to the accompanying drawing.

10 This invention relates to a scoop washing cylinder and particularly to a construction and arrangement of the buckets formed thereon for introducing and discharging liquid from the cylinder during its rotation.

15 The invention has for an object to provide a novel construction of cylinder for washing and other similar machines having a series of buckets merging into rubbing ribs disposed intermediate of successive buckets of the 20 series, and further to form the edges of the openings of the buckets with one of said edges straight and the other curved, the ends of the openings being formed on curved lines and extending out the plane of the 25 body of the plate.

Other and further objects and advantages of the invention will be hereinafter set forth and the novel features thereof defined by the appended claims.

30 In the drawings—Figure 1 is a detail perspective of a portion of a cylinder formed in accordance with this invention; Fig. 2 is an enlarged section extending longitudinally of the buckets; Fig. 3 is a similar section extending transversely of the buckets; Fig. 4 is a plan of the inner face of the plate having portions embossed to form buckets; Fig. 5 is a similar view of the slotted plate before the embossing action; and Fig. 6 is a detail 35 of the completed plate formed as a cylinder.

Like numerals of reference refer to like parts in the several figures of the drawings.

For the purpose of illustration, this invention is shown in connection with a washing machine but is equally applicable to a drying tumbler and dyeing and similar machines in which a cylinder is used having a series of apertures with buckets disposed at one side thereof to introduce and discharge liquid 45 from the cylinder in a succession of streams.

The numeral 10 indicates a metallic plate which is curved into the form of a cylinder and supported at each end by the heads 11 carrying the trunnions 12. The cylinder

plate 10 is formed with a continuous series 55 of openings 13 disposed in a single circumferential line, the boundaries thereof being merged into each other forming intermediate rubbing ribs 14 between successive openings having convexed rubbing faces. At one side 60 of each opening, the body of the plate is embossed or swaged outward to form a bucket 15 having a free edge 16 curved transversely and longitudinally. The opposite edge of the opening 13 is formed with an 65 outwardly curved flange 17 extending beyond the plane of the plate 10, the edge of this flange being straight relative to the curved edge 16 of the bucket, as shown at 18 in Figs. 2 and 6. To prevent the collection 70 and holding of lint or other material, the ends of the opening 13, where the walls of the bucket 15 and the flange 17 merge, are curved as shown at 19. The base of the bucket 15 and flange 17, where they are 75 merged outward from the rubbing ribs 14, is curved as shown at 20 and 21, respectively, thus presenting curved faces at opposite sides of the rubbing rib, the face 20 being curved longitudinally of the rib, while the 80 face 21 is curved outward upon a straight line, as shown in Fig. 4. The cylinder is provided with a plurality of series of buckets, those of one series being extended in a single 85 circumferential line and in the same direction, while those of the next adjacent series are disposed in a similar line but in an opposite direction, thus providing an intermediate plane portion 23 upon the cylinder which prevents interference in the discharge or 90 introduction of liquid by the buckets of each series. These buckets may be formed in any desired manner, for instance by slotting or punching a plate with a series of openings 95 13, as shown in Fig. 5, these openings being subsequently embossed or swaged to form the buckets and raised flanges as shown in Fig. 6. These mechanical steps may be formed by any desired tool or machine.

In the prior art, it has been customary 100 to provide a cylinder with a series of buckets formed therefrom, some of these buckets being disposed in one direction and the others in the opposite direction; and the present invention comprises an improvement 105 upon the arrangement and form of these buckets whereby those in one series are spaced from each other and merge into in-

termediate rubbing ribs disposed between successive buckets, while each series of buckets is separated by a plane portion of the cylinder so as to permit a free flow of liquid to and from the buckets, so that the series of small streams passing from the buckets produces a continuous circulation within the cylinder and the streams do not impinge against each other. The rubbing ribs provide a surface by which a scouring or rubbing action upon the articles within the cylinder is secured which more quickly cleanses them and greatly increases the working capacity of the machine. The formation of the edges of the bucket openings provides curved faces for the rubbing ribs and the curving of the ends of these openings where the bucket and flange merge, prevents the collection of lint or other material and also any injury to the articles within the cylinder in case they be drawn or forced into contact with the openings as these ends avoid the sharp or wedge shaped portion liable to catch and hold the material.

The invention, therefore, presents a simple, efficient and economically constructed form of cylinder for washing and similar machines having a series of buckets formed from the material thereof and adapted to introduce and discharge liquid from the cylinder in a continuous series of jets which draw the articles into contact with the rubbing ribs.

Having described my invention and set

forth its merits what I claim and desire to secure by Letters Patent is:

1. A cylinder for washing or similar machines having slots cut therein, flanges exterior of the cylinder and extending along one side and both ends of said slots and merging into buckets formed from the body of the cylinder on the other side of said previously cut slots, the part of the cylinder between a flange and bucket being curved to produce a rounded rubbing rib.

2. In a washing machine, a cylinder provided with a number of circumferentially disposed series of buckets struck up outwardly from the body of the cylinder in close relation to each other, the body of the cylinder between the buckets in a series thereof having a convexed conformation, the convexity of which is opposite that of the curvature of the cylinder, whereby a curved rubbing rib is provided between each pair of buckets in the series.

3. A cylinder for a washing or similar machine provided with a bucket formed from the body of the cylinder with the edges of the opening of the bucket disposed out of the plane of the body of the cylinder, the ends of said openings being formed upon curved lines.

In testimony whereof I affix my signature in presence of two witnesses.

WILLIAM BARTHOLOMEW.

Witnesses:
